1

The making of a gown to measure, in accordance with the conventional models designed by a dressmaker requires numerous operations performed in the workroom as well as in the fitting-room, and consequent results in a high manufacturing cost and in a rather long time for completing the work.

Such gowns are made by assembling, in accordance with the model chosen by the customer, a certain number of pieces or panels of fabric cut out to measure. This requires a previous cutting out and adjustment of panels or pieces of linen of the pattern corresponding to the model, this adjustment comprising the following main operations: pinning together the pieces of linen; sewing the threads indicating the measurements; unpinning; laying flat the linen panels over the fabric; pinning together the linen panels and the fabric; cutting out the fabric along the outline of the linen panels; marking, on the fabric, the sketching of the measurement threads; unpinning the linen panels and the fabric panels; fitting together the fabric panels by sewing or basting on a wooden or cardboard dummy; and only then the customer undergoes the first trying-on. In order to effect readjustments, after this first trying-on it is necessary to carry out further numerous operations. These operations are liable to occur over and over again in the case of readjustments requiring two or more trying-ons, and it may be understood that making a gown by conventional method takes a long time and results in considerable labor and expense.

In order to overcome these drawbacks, I have devised a new cutting to measure technique and enables me to make very rapidly, gowns belonging to a wide range of models, at a relatively low cost.

This technique consists in:

(a) Making linen patterns in accordance with conventional sizes and with the various models, each pattern comprising, in a single piece, the front and rear parts of the gown, and having a conveniently cut out outline bearing indentations which demarcate on one side thereof, bodice fastening straps level with the waist, and on the other side thereof skirt portions, some of these straps and skirt portions being designed to be brought either forwards or backwards, around the body in order to form the gown;

(b) Trying on the customer the pattern thus cut out which corresponds best to her nearest dummy size and adapting the pattern to her body by altering, through pinning, the size and position of the straps and skirt portions and, if

2

necessary by pleating at appropriate places, or if the pattern is deprived of straps level with the waist, by marking on this pattern with a ribbon, the location of the waist and the waist-measure.

(c) Laying flat the linen pattern on the pieces of fabric and cutting out said piece along the outline of the pattern, so as to constitute a panel comprising, in a single unit, the front and rear parts of the gown, and occasionally pleating conveniently according to the adjustment marked on the pattern;

(d) Completing the gown, in particular by providing at the ends of the straps and skirt portions, buttons, press-buttons or other removable fastening means.

The customer fits on the gown thus completed and, if need be, it is finished by pleating.

This technique produces seamless gowns made to measure characterized by a single panel comprising the front and rear parts, the bodice and the skirt being fastened by means of buttons, press-buttons, zip fasteners or other device excluding seams. Such a gown whose model can vary indefinitely constitutes a new industrial product.

In case the customer's size does not fall within one of the conventional dummy sizes, it will be sufficient, for carrying out the process, to cut out a pattern in accordance with measures taken on the customer.

It is to be noted that according to the process the invention and contrary to the technique at present used in high-class dressmaking:

(a) The customer's measures need not be taken as a rule; she merely tries on the pattern whose dummy size is nearest to hers;

(b) As the gown bears no seams, except for added sleeves in certain models, a single trying-on of the pattern is enough, this trying-on being effected for instance during the first call of the customer at the dressmaking shop; the gown may therefore be delivered without her having to come back.

According to a form of the invention, the pattern is cut out in such a way that the completed gown has the shape of a chasuble, the front panel and the rear panel being made of a single piece, and comprising at their sides, two indentations demarcating bodice fastening straps and two skirt portions, said straps and skirt portions being provided with buttons and button-holes. By alternately bringing forwards and backwards the straps and the skirt portions, around the body, a seamless gown is constituted as described hereafter.

By varying the number of button-fasteners,

the number, the disposition, and the shape of indentations and, as a consequence, those of the straps and of the skirt portions, by folding back certain skirt portions, by doing without certain straps or skirt portions, etc. an indefinite variety of seamless gown models may be designed.

As regards the button-fasteners it is to be noted that, for a straight seamless gown whose pattern is of the chasuble type and comprises two button-fasteners one for the skirt and the other for the bodice, it is possible to have both button-fasteners in front, or both button-fasteners at the back, or one button-fastener in front and the other at the back, and vice versa, which clearly provides for four possible different forms. In each of them, both button-fasteners may be apparent, or one of them may be hidden, thus giving rise eventually to twelve possible forms. In case the gown comprises three button-fasteners, it may be shown that the number of possible forms is sixteen.

Other objects and advantages of the invention will be apparent during the course of the following description. In the accompanying drawing forming a part of this application and in which like numerals are employed to designate like parts throughout the same.

Fig. 1 illustrates, in flat laid position, a pattern relative to a model of seamless gown,

Figs. 2 to 6 are diagrams illustrating the way in which the above gown is fitted on,

Fig. 7 is a view similar to Fig. 1 of a pattern relative to a further model of gown.

Fig. 8 shows the fitting-on of this latter pattern,

Fig. 9 illustrates the way in which this pattern is adjusted to the customer's body, and

Figs. 10 and 11 are relative to a seamless sleeve.

According to the first form of the invention (Figs. 1 to 6), a linen pattern *a* is designed as shown in Fig. 1. It is made of a single piece of linen whose length *l* equals, or is slightly greater than, twice the height of the gown, thereby embodying both the front and rear panels of the gown; half-way along this pattern, an opening *b* provides for the neck-line. Taking as origin point *b*₀ at the tip of the opening corresponding to the nape of the neck, the shoulder line *Z-Z* is determined; the pattern is to be folded along this line when fitted on.

Moreover the pattern is cut out so as to form two indentations *b*₁, *b*₂, the portion of the outline between these indentations assumes the shape of a curved line *h*, at first concave (starting from either of the indentations), and then convex level with the opening. The shape of this outline is determined by the chest-measure 1, about 25 to 30 cms. from line *Z-Z*, and by the breadth 7 across the shoulders, about 10 cms. from *b*₀. These indentations demarcate two straps *c*₁, *c*₂, whose vertical distance from the shoulder line *Z-Z* is determined by the bust length 4, for the front as well as the back; if the bodice is to bear a ripple in the back, the dimension 4a will be greater than the dimension 4 according to the size of the ripple. The length of straps *c*₁, *c*₂, i. e. the distance between the axis *X-X* and the end of the strap, is determined by the waist-measure 2. The indentations *b*₁, *b*₂ also demarcate portions *d*₁, *d*₂ of skirt panels *D*₁, *D*₂. The width of these panels is determined by the hip-measurer 3.

An allowance edge *f* is provided around the outline *e* which corresponds accurately to these measures.

A certain number of linen patterns are thus made to correspond to the various conventional dummy sizes.

When a customer chooses a gown whose model 5 corresponds to the pattern of Fig. 1, the pattern whose size is nearest to hers is selected from the premanufactured patterns. This pattern is fitted on, line *Z-Z* coinciding with the shoulder line. The front panel *D*₁ being previously raised the portion *d*₂ of the rear panel *D*₂ is brought forwards and pinned. The bodice strap *c*₁ is brought backwards around the waist. If it is not accurately in position, its height is adjusted by 10 acting on the edge *f*; its length is also adjusted by appropriate pleats. This strap is pinned in its final position. The portion *d*₁ of the front panel *D*₁ is brought backwards, and its height and width are adjusted by pinning. The strap *c*₂ is similarly brought forwards around the waist 15 adjusted, and secured by means of pins. The pattern may be pleated along the waist, as shown in dotted lines in *g*.

In other words, the pattern is adjusted on the 20 customer's body by pinning appropriately and by 25 effecting at the desired places, pleats in convenient number and size.

The adjustment of the sleeves is carried out in 30 a similar way by altering, through pinning, the shape of the curved portion *h* of the pattern, so that the latter fits accurately on the customer's shoulders and arms. Obviously all necessary indications may be marked on the pattern for the purpose of reconstituting accurately the gown in accordance therewith.

35 The pattern is then laid flat upon the piece of fabric which is longitudinally folded, the line *X-X* of the pattern coinciding with the median axis of the piece of fabric. The latter is cut out along the outline of the pattern, thus forming 40 straps *c*₁, *c*₂ and skirt portions *d*₁, *d*₂ (this is the case, of course, of a gown symmetrical about its longitudinal axis). The gown is completed by arranging the buttons, the button-holes, the petershams, etc. It appears, in open position, as 45 a chasuble which the customer slips on by passing her head through opening *b*, as illustrated in Fig. 2 which shows:

Both the front skirt portion *d*₁ and the rear one *d*₂,

50 Both the bodice straps *c*₁ belonging to the front panel of the gown and those *c*₂ belonging to the rear panel,

The four button-fasteners *k*₁ for the rear skirt portion, *k*₂ for the straps *c*₁ of the front panel, *k*₃ for the front skirt portion, and *k*₄ for the straps *c*₂ of the rear panel.

55 Figs. 2 to 6 illustrate in which manner this seamless gown is fitted on and fastened.

The chasuble being in position and stretched out, as shown in Fig. 2, the gown is fastened in 60 four steps:

1st step (Fig. 3): Both portions *d*₂ of the rear panel are brought forwards, around the waist, underneath the front panel *D*₁ (button-fastener *k*₁), in order to form the skirt. For clearness' sake, the front panel *D*₁ is assumed to be cut level with the chest along line *A-A*.

65 2d step (Fig. 4): Both bodice straps *c*₁ of the front panel are brought backwards around the waist and buttoned up at the back (button-fastener *k*₂). For clearness' sake, the rear panel is assumed to be transparent above line *B-B* and its outline is shown in dotted lines; moreover the front panel *D*₁ is seen stretched out, 70 so that the inner side of portions *d*₁ is apparent.

3d step (Fig. 5): The portions d_1 of the front panel are brought backwards and buttoned up at the back (button-fastener k_3).

4th step (Fig. 6): The straps c_2 of the back panel are brought forwards around the waist and are buttoned up (button-fastener k_4).

By resorting to the pattern shown in Fig. 1, it is possible to constitute numerous different models as follows:

According to a first form, both portions d_1 of the front panel D_1 are folded forwards instead of being buttoned up at the back, and they will be buttoned up at the central part of the front panel, as shown in dotted lines x , in Fig. 2.

According to a further form, the front panel is done without from the waist down, the skirt portions of the rear panel being then brought forwards and buttoned up along the entire height.

According to a further form, the front panel is slashed from the neck-line down to the waist, thus allowing for wide facings; or it may be slashed from the waist down, thus giving rise to flaps; or still it is slashed from the neck-line down to the bottom.

Figs. 7, 8, 9 show another pattern of a model wherein the front and rear panels are made of a single seamless piece and to which sleeves can be added. This pattern has a height H corresponding to that of the gown. The front skirt portion d_1 and the front and rear panels D_1 and D_2 , are shown on this pattern.

The outline of this pattern comprises but one indentation b_3 along its height and one indentation b_4 on its upper edge, the latter being designed for the sleeve.

This pattern is fitted on as shown in Fig. 8, the vertical line $y-y$ (substantially bisecting indentation b_4) being located in the middle of the hip, the parts n and o of the upper edge being pinned together above the customer's shoulder.

The waist is then adjusted by pleats p whose position is determined by a ribbon q pinned around it. The length of this ribbon allows the transfer to the piece of fabric, after laying flat the pattern and cutting out the fabric, of the pleats p . The front skirt portions d_1 protrude laterally with respect to the vertex v of indentation b_3 —this vertex must lie on the vertical median axis of the gown—so that they overlap and are buttoned up on top of one another.

In this model, the completion of the gown only requires a small seam along lines n and o over the shoulders; this seam may nevertheless be done without and a zip or other removable fastening means may be substituted therefor.

In this model, the added sleeve can be constituted as shown in Figs. 10 and 11, i. e. without seams. For this purpose, a substantially triangular panel s is used which is sewn to the shoulder of the gown and whose flaps s_1 , s_2 are designed to be rolled up in opposite directions (along the arrows of Fig. 10), around the customer's arm (in the same way as the straps c_1 , c_2 of the model corresponding to Fig. 1, were rolled around the waist) and are buttoned up in t on top of one another. The sleeve thus formed can be moved up by pleating, on the customer's forearm.

Obviously the invention is not to be restricted to gowns, but extends to any dress whose front and rear panels consist of a single piece of fabric.

It is to be understood that the form of the in-

vention herewith shown and described is to be taken as a preferred example of the same and that various changes to without departing from the spirit of the invention or the scope of the subjoined claims.

What I claim is:

1. A gown of the class described, formed of a single piece of material, the general outline of which when laid flat is rectangular, including an intermediate bodice section and two skirt sections on both sides of said bodice section, and having an approximately central aperture through which the wearer's head is to be passed to permit said material to fall in front and at the rear of the wearer, the end sides of the piece of material constituting the bottom of the skirt sections, said piece of material being cut to form inwardly extending sides at a distance from said end sides corresponding to the waist of the wearer, and to provide two pairs of laterally protruding, opposite, cooperating straps extending within said rectangular general outline, respectively in the front part and in the rear part of the piece of material, at a distance from the central aperture corresponding to the bust-length of the wearer, the sides of said straps remote from the central aperture extending inwardly to meet the said inwardly extending sides of the skirt sections, and the other sides of adjacent straps being connected to each other along a generally concave-convex-concave curved line, the opposite cooperating straps of each pair comprising, in the vicinity of the ends thereof, means for fastening same, whereby the cooperating straps in the front part of the piece of material are adapted to be fastened at the back of the wearer and the cooperating straps in the rear part of the piece of material are adapted to be fastened at the front of the wearer.

2. The gown according to claim 1, wherein the inwardly extending sides in the rear part of the piece of material extend further inwards than the inwardly extending sides in the front part of the piece of material.

3. The gown according to claim 1, wherein the said inwardly extending sides are substantially perpendicular to the lateral sides of the skirt sections.

4. The gown according to claim 1, wherein the meeting, inwardly extending sides form an acute angle.

5. The gown according to claim 1, wherein the distance between the fastening means of cooperating straps is equal to the waist-measure of the wearer.

6. The gown according to claim 1, wherein the cooperating straps in the front part of the piece of fabric are nearer the central aperture than the cooperating straps in the rear part of the piece of fabric.
